UNITED STATES PATENT OFFICE

164,618

GOBLET

Robert A. Yuchtmann, Fairmont, W. Va.

Application April 12, 1950, Serial No. 9,154

Term of patent 14 years

(Cl. D36—8)

To all whom it may concern:

Be it known that I, Robert A. Yuchtmann, a citizen of the United States of America, residing at Fairmont, in the county of Marion and State of West Virginia, have invented a new, original, and ornamental Design for a Goblet, of which the following is a specification, reference being had to the accompanying drawing, forming a part thereof, wherein:

Figure 1 is a perspective view of a goblet embodying my new design;

Fig. 2 is a view in side elevation; and

Figure 3 is a cross-sectional view thereof, taken on the line 3—3 of Figure 1.

The dominant feature of the design resides in the goblet stem merging smoothly at its upper end into the bowl portion of a goblet and terminating abruptly against a base at its lower end, as shown.

I claim:

The ornamental design for a goblet, as shown and described.

ROBERT A. YUCHTMANN.
